UNITED STATES PATENT OFFICE.

JEAN SCHWEITER, OF HORGEN, SWITZERLAND.

SCOURING-MACHINE FOR WOVEN FABRICS.

SPECIFICATION forming part of Letters Patent No. 757,148, dated April 12, 1904.

Application filed March 5, 1902. Serial No. 96,868. (No model.)

To all whom it may concern:

Be it known that I, JEAN SCHWEITER, manufacturer, a citizen of the Swiss Confederation, residing at Horgen, Switzerland, have invented 5 certain new and useful Improvements in Scouring-Machines for Woven Fabrics, of which the following is a specification.

The present invention relates to a scouring-machine for woven fabrics, the essential feature of which is that the scouring-knives are all together or by rows pressed by an elastic pressing medium against the textile fabric, the intensity of the pressure being liable to be regulated by alterations of the tension in 15 the pressing medium.

In the drawings, which by way of example represent one form in which the invention can be carried out, Figure 1 shows a vertical section through the scouring-machine; Fig. 2, a 20 vertical longitudinal section through the same on the line II II, uncovered on various places and in which all parts not necessary for the understanding of the invention have been omitted. Fig. 3 shows a vertical longitudinal 25 section through a single scouring device, the middle part of which is imagined as left out. Fig. 4 shows a vertical longitudinal section through the same on the line IV IV of Fig. 3 and seen from the left side; Fig. 5, a horizontal 30 longitudinal section on the line V V of Fig. 3; and Fig. 6 shows a special design of the elastic cushions.

As per Fig. 1, the stuff-beam 8, from which the textile fabric 9 to be treated is rolled off, 35 is journaled in the bearings 6 of the machine-frame 7. From the stuff-beam 8 the fabric runs over a guide-roller 11, rotatively journaled in the bearing-arms 10, screwed to the machine-frame. Thence the fabric passes between a guide formed by the rails 12, 13, 14, 40 and 15 and the knives 16, 17, 18, and 19, arranged in consecutive rows, to the front guide-roller 20, rotatively journaled in the bearing-arms 21, screwed to the machine-frame. From 45 this guide-roller 20 the fabric 9 is guided downward to the winding device, which consists of the rollers 22, 23, 24, and 25, and may be of any suitable construction. The rollers 22 and 23 are spreading-rollers. They are 50 journaled at both ends in a lever 26, pivoted at 27 in the machine-frame and weighed by

a counterpoise 28 in such a manner that the roller 23 is pressed from beneath against the winding-beam 24. By a suitable device the latter receives a continuous or an intermittent 55 rotatory movement. The roller 25 is journaled in slotted bearings 29 of the machine-frame and rests on the winding-up beam 24 or on the wound-up fabric.

As will especially be seen by Figs. 3 and 4, 60 the knives 16, 17, 18, and 19 are each fastened to a carrier 30. The carriers 30 of each row of knives or of two or more rows of knives are pivoted at 32 to a common plate or the knife-carrier 31 and linked by rods 33 with 65 bow-shaped sliders or shoes 34. These shoes 34 are fixed to levers 35, adapted to rotate round the trunnions 36, which latter are secured beneath the plate 31. The shoes 34 rest on one or more hose 37, which latter are preferably located in a box 38, the cover of which 70 may be formed by the aforesaid plate 31. The ends of the hose are closed by stoppers, the end stopper 39 being fixed by means of a screw 40 to the front wall 41 of the box 38, whereas the 75 other stopper, 42, is hollow and passes through the wall 43 of the box 38. In the hitherto-described design the channels in the stoppers 42 belonging each to two hose 37 communicate with each other through a cross-channel 80 44, Figs. 3 and 5, and the two outer ones of the hose located in one box communicate with each other through a piping 45, connected to a main pipe 46. Through this piping and by means of a convenient pressing device air or 85 water under pressure is fed to the hose. For such purpose the piping 46 can be connected by flexible tubing to a compressed-air piping existing in the workshop; but the compressed air may as well be produced by the machine 90 itself, as it is designed to be the case in Figs. 1 and 2. A pneumatic pump 47, driven by the machine by means of shafting and a crank, presses the air direct or by insertion of an air-pressure tank 48 through the flexible tubes 95 or hose 49 in the aforesaid piping 46 of the scouring device. By cocks 55 inserted into the tubes the admission of the air can be stopped in due time as soon as the air-pressure has reached the required amount. The dis- 100 tended hose 37 thus forms elastic cushions which determine with the aid of the aforescribed

intermediate organs the amount of pressure at which the knives 16, 17, 18, and 19 act upon the textile fabric 9 passing over them.

The knives 16, 17, 18, and 19 receive a reciprocating movement perpendicular to the direction in which the fabric moves. For such purpose the boxes 38 intended for holding the entire scouring device are provided at their bottom part with guide-rods 50, Figs. 1 and 2, which slide on the cross-bars 51 in the machine-frame. Upon each box 38 acts a crank-rod 53, driven by a crank 52. In two scouring devices or more arranged in series the cranks 52 are placed on the shaft 54 at one hundred and eighty degrees for the purpose of giving the scouring devices two movements opposed to each other. The knives of one scouring device are then placed, as may be seen from Fig. 2, in opposition to the knives of the other scouring device, thus allowing the knives of the first device to scour the fabric from the center to one side and those of the second device to treat it from the center to the other side. The shaft 54 receives its rotary movement from the main shaft 56 of the machine. As per Fig. 1, the main shaft 56 drives with the aid of beveled gear 57 an intermediate shaft 58. A spur-gear 59 on this shaft engages with a spur-gear 60 on the shaft 54. On the end of the intermediate shaft 58 a crank 61 is located, which drives the pneumatic pump 47. From the main shaft 56 a shaft 65 is driven by means of the chain-wheel 62, the chain 63, and the chain-wheel 64. On the said shaft 56 the groove-cams 66 are located, which lift and lower sliding bars 67, vertically guided in the machine-frame. These bars are screwed to the frame 68, which carries the guide-rails 12, 13, 14, and 15 for the woven fabric. The rails 12, 13, 14, and 15 have thus a raising-and-lowering movement which has a determined ratio to the reciprocating movement of the knives 16, 17, 18, and 19.

In the selected design it is, as already mentioned, supposed that the knives 16, 17, 18, and 19 are under pneumatic pressure, and at the beginning of the work the hose 37 are blown out to a definite degree. If now the machine is started, the aforescribed movements of the single devices will take place. The scouring devices move in two directions opposite to each other and are at certain times brought into contact with the fabric. At the time when the two scouring devices are approaching each other the guides 12, 13, 14, and 15 for the fabric have reached their lowest position and remain in same, in consequence of the shape of the groove-cams, as long as the scouring devices are moving forward. The knives 16, 17, 18, and 19 will then pass across the fabric brought into contact with them, and the pressure at which the knives are pressed against the fabric is perfectly steady. Every single knife, however,

can come to close contact with the fabric independently of all others. At the moment where the scouring devices reach the end of their stroke the fabric-guides 12, 13, 14, and 15 are lifted again to prevent the knives 16, 17, 18, and 19 from touching the fabric on their way back.

As a matter of course the pressure of the compressed air within the hose can be altered at pleasure, whereby the force with which the knives are pressed against the fabric can be modified according to want.

Instead of compressed air any other compressed gas or fluid may, of course, be filled into the hose 37 to serve as a pressure-medium. It is likewise quite indifferent whether the hose 37, designed for storing up the medium of pressure, be substituted by elastic cushions of any desired shape. Fig. 6, for instance, shows the section of another very suitable shape of a cushion. The bottom part 69 may be a metal or wooden box, which is covered at the top by a casing 70, flexible under air, gas, or fluid-pressure.

What I claim, and as my invention desire to secure by Letters Patent of the United States, is—

1. In a scouring-machine for woven fabrics, the combination with an elastic cushion adapted to be distended by fluid-pressure, of transversely-reciprocating knives constructed to be steadily pressed against the fabric by said cushion.

2. In a scouring-machine for woven fabrics, the combination with the knife-carrier and knives pivotally arranged on a knife-carrier, of a pressing-cushion adapted to act elastically through the introduction of a fluid-pressure medium, shoes supported on the cushions, and linked connections between the shoes and the knives, substantially as described.

3. In a scouring-machine for woven fabrics, the combination with a plurality of scouring devices comprising knives arranged in consecutive rows, and elastic cushions, the number of which corresponds to the number of knife-rows, which cushions are adapted to hold a fluid-pressure medium and against which the corresponding knife-rows bear, of means for moving adjacent scouring devices in opposite directions, and vertically-movable fabric-guides bringing the knives into contact with the fabric only in one direction of movement, as and for the purpose set forth.

4. The combination with the transversely-moving knives, of fabric-guides movable to bring the fabric into contact with the knives only in one direction of movement of said knives.

In witness whereof I have hereunto set my hand in presence of two witnesses.

JEAN SCHWEITER.
